J. MARTIN

BRICKLAYER'S HAMMER

Filed April 9, 1927

Inventor
John Martin,

By Clarence O'Brien
Attorney

UNITED STATES PATENT OFFICE.

JOHN MARTIN, OF PARKERSBURG, WEST VIRGINIA.

BRICKLAYER'S HAMMER.

Application filed April 9, 1927. Serial No. 182,415.

The present invention relates to improvements in bricklayers' hammers and has reference more particularly to a simple and efficient means for securing the handle to the 5 head of a hammer.

One of the important objects of the present invention is to provide a tool handle fastening which is of such construction as to permit the handle to be readily and easily 10 attached or detached with respect to the head of the hammer, means being provided for rigidly securing the handle to the head so that the same cannot become accidentally disengaged therefrom while in use such as frequently 15 results with the type of tool handle fastenings now generally employed for connecting a handle to a hammer head.

A further object of the invention is to provide a tool handle fastening of the above 20 mentioned character which is simple in construction, inexpensive, and furthermore adapted to the purposes for which the same is designed.

Other objects and advantages of this invention will become apparent during the 25 course of the following description.

In the accompanying drawing forming part of this specification and in which like numerals are employed to designate like 30 parts throughout the same:

Figure 1 is a view partly in elevation and partly in section of a bricklayer's hammer embodying my invention showing the tool handle fastening means associated therewith.

Figure 2 is a vertical sectional view taken approximately on the line 2-2 of Figure 1 for more clearly disclosing the cooperating 35 means between the handle and the hammer head for preventing the lateral sliding movement of the handle with respect to the head,

Figure 3 is a sectional view taken approximately on the line 3-3 of Figure 1, and

Figure 4 is a sectional view through the block carrying rod or shank showing the rotatable and slid able upper section of the handle in top plan.

In the drawing wherein for the purpose of illustration is shown the preferred embodiment of my invention, the numeral 1 designates the head of a bricklayer's hammer, the handle being designated generally by the 50 numeral 2. Formed on one face of the head 1 adjacent the headed end thereof are the spaced transversely extending lugs 3 and 4 respectively. The inner opposed sides of

these lugs are tapered whereby to form a substantially dove-tailed recess 5 in said face of the head 1 and the purpose thereof will be presently apparent. Each lug is formed with a recess at 6 in the outer face thereof and this is clearly shown in Figure 1 of the drawing.

The handle 2 includes the provision of an elongated rod or shank 7 which is externally threaded at its respective ends. The handle further includes the sections 8 and 9 respectively, and each of these sections is formed with a longitudinally extending bore to accommodate the elongated rod or shank 7. The outer end of the outermost section 9 has 70 its bore enlarged and fitted therein is the elongated sleeve 10, the same being formed at its outer end with enlarged base 11 which engages the outer end of the section 9.

The sleeve 10 is internally threaded as illustrated at 12 and the outer threaded end of the rod 7 is threaded into this sleeve in the manner clearly shown in Figure 1. The inner end of the outermost section 9 is reduced as illustrated at 13 while the outer end of the section nearest the tool has its bore enlarged to accommodate the reduced portion 13 so that the outer end of the section 8 will abut the shoulder 14 formed at the juncture of the section 9 with the reduced portion 13 when the section nearest the tool is in its outermost position on the rod or shank 7.

This section 8 is adapted for rotatable as well as longitudinal slid able movement on the inner portion of the rod or shank 7 for 90 a purpose to be presently described. The inner portion of this section 8 is enlarged to provide the head 15 and this head is provided with a pair of diametrically opposed flat faces in a manner more clearly shown in 95 Figures 1 and 4 of the drawing. Formed on the face of this enlarged head 15 at diametrically opposite points are the projections 16 and the purpose of these projections is to provide a means for cooperation with the slots 6 formed in the outer faces of the lugs 3 and 4 as will be also presently described.

A flat faced block 17 is formed with a threaded socket in one face thereof to receive the inner threaded end of the rod or shank 7 105 whereby said block will be carried by the inner end of the rod or shank and the sides of this block are tapered so that the same is substantially dove-tailed in cross section as is clearly disclosed in Figure 1.

In assembling the hammer, the section 9 of the handle is rotated so as to cause said sections to move outwardly on the shank or rod 7 and this is done until the free ends of 5 the projections 16 formed on the face of the enlarged head 15 on the free end of the inner section 8 of the handle are disposed outwardly of the outer face of the dove-tailed block 17. The dove-tailed block 17 is then 10 free to be slid laterally between the lugs 3 and 4 of the hammer head 1 whereby said dove-tailed block 17 will fit in the dove-tailed recess 5 provided therefor by the co-operating lugs 3 and 4.

15 After the block has been properly positioned in the recess, the section of the handle nearest the tool is then rotated until the projections 16 are in alignment with the slots 6 formed in the faces of the lugs. The section 20 8 is then moved inwardly on the shank so that said projections will enter the respective slots and the inner faces of the projections are beveled for cooperation with the adjacent beveled sides of the tapered block 17. The 25 outermost section 9 is then rotated in a reverse direction for moving said section inwardly on the shank so that the inner end of the outermost section will engage the outer end of the innermost section and thereby 30 lock the latter against longitudinal movement. When the parts are thus arranged, the projections 16 will cooperate with the sides of the slots 6 formed in the lugs to prevent the handle and the dove-tailed block 35 from being accidentally moved laterally with respect to the head 1 and thereby, the dove-tailed head will be held in locked engagement within the dove-tailed recess 5 thus providing a positive connection between the handle 40 2 and the hammer head 1. The hammer may then be used in the usual manner and there will be no possibility of the handle becoming accidentally disengaged from the hammer head.

45 Whenever it becomes necessary to dis-assemble the parts of the hammer, the outermost section 9 of the handle 2 is rotated so that the same will move outwardly a sufficient distance on the rod or shank 7 to permit the innermost section 8 to also move 50 on the rod whereby the projections will be disengaged from the notches or slots formed in the lugs and the dove-tailed block 17 may then be moved laterally out of engagement 55 with the dove-tailed recess 5.

It will thus be seen from the foregoing description, that I have provided a tool handle fastening for use principally in connection with bricklayers' hammers although the 60 same may be used in connection with any other type of tool embodying a head and a handle. This tool handle fastening will at all times be positive and efficient in carrying out the purposes for which it is designed and 65 furthermore, due to its simplicity, it may be

readily and easily actuated for dis-assembling the parts of the hammer or tool without the loss of any considerable length of time or labor.

While I have shown the preferred embodiment of my invention, it is to be understood that various changes in the size, shape and arrangement of parts may be resorted to without departing from the spirit or sacrificing any of the advantages of the appended 70 75 claims.

What I claim is:—

1. In a tool, a handle, a head, the head being provided with a dove-tailed recess in one face thereof, a dove-tailed block carried by 80 the inner end of the handle for slidable engagement within the dove-tailed recess, and cooperating means between the handle and the head for locking the block in said recess against lateral sliding movement.

2. In a tool, a head, a handle therefor, said head being provided with a dove-tailed recess in one face thereof, said handle including a rod, inner and outer sections through which the rod extends, a block secured on the inner end of the rod, said block being dove-tailed for slidable engagement within the dove-tailed recess of the head, and cooperating means between the free end of the inner section of the handle and the head 90 95 for locking the dove-tailed block in the dove-tailed recess against lateral sliding movement.

3. In a tool, a head, a handle therefor, said head being provided with a dove-tailed recess in one face thereof, said handle including a rod, inner and outer sections through which the rod extends, a block secured on the free end of the rod, said block being dove-tailed for slidable engagement within the dove-tailed recess of the head, and cooperating means between the free end of the inner section of the handle and the head for locking the dove-tailed block in the dove-tailed recess against lateral sliding movement, said 100 105 means comprising projections extending from the free end of the inner section, the inner face of the head being formed with recesses which communicate with the dove-tailed recess and into which the projections extend, the inner faces of the projections adapted to engage the adjacent faces of the dove-tailed block.

4. In a hammer, a head, a handle, a pair of spaced lugs formed on one face of the head, the inner opposed sides of the lugs being tapered to provide a dove-tailed recess, said handle including an elongated rod, inner and outer sections arranged on the rod, the inner section being adapted for longitudinal movement on the rod, a dove-tailed block carried by the inner end of the rod adapted 110 115 for slidable engagement between the lugs for disposition within the dove-tailed recess, and cooperating means between the lugs and 120 125 130 135

the free end of the inner section of the handle for locking the dove-tailed block in the recess against lateral sliding movement.

5. In a hammer, a head, a handle, a pair of spaced lugs formed on one face of the head, the inner opposed sides of the lugs being tapered to provide a dove-tailed recess, said handle including an elongated rod, inner and outer sections arranged on the rod, the inner section being adapted for longitudinal movement on the rod, a dove-tailed block carried by the inner end of the rod adapted for slideable engagement between the lugs for disposition within the

dove-tailed recess, and cooperating means 15 between the lugs and the free end of the inner section of the handle for locking the dove-tailed block in the recess against lateral sliding movement, said means comprising a pair of projections formed on the free end 20 of the inner section of the handle, the outer faces of the lugs being formed with recesses which communicate with the dove-tailed recess and into which extends the projections, the inner opposed faces of the projections 25 engaging the sides of the dove-tailed block.

In testimony whereof I affix my signature.

JOHN MARTIN.
